DENTAL FLOSS HOLDER

John R. Russell, 305 Conifer Court,
Walnut Creek, Calif. 94598

Filed Nov. 4, 1968, Ser. No. 14,299

Term of patent 14 years

Int. Cl. D24—03

U.S. Cl. D24—1

FIG. 3

FIG. 2

FIG. 1

FIG. 5

FIGURE 1 is a front elevation of a dental floss holder, the opposite rear side being a mirror image of the front; FIGURE 2 is a side elevation thereof;

The dominant features of my design reside in the portions shown in full lines.

I claim:

The ornamental design for a dental floss holder, as shown and described.
